UNITED STATES PATENT OFFICE.

JAMES F. COSTELLO, OF SAN FRANCISCO, CALIFORNIA.

FORM CLAMP.

Application filed May 11, 1925. Serial No. 29,300.

This invention relates to form clamps and especially to improvements on the structure shown in my co-pending application entitled "Form clamp", Serial Number 5,282, filed 5 January 28, 1925.

The clamp forming the subject matter of my co-pending application, and other clamps which are particularly adapted for use in clamping together the several parts of concrete forms such as column forms and the like, are generally used on forms which are square in cross section, and when the clamps are applied and drawn together it is found that considerable care must be taken as the 15 forms are otherwise pulled out of square.

The object of the present invention is to generally improve and simplify the construction and operation of the clamp of the character described, and particularly to provide 20 a connection between the clamping sections which will insure a right-angular position or any other predetermined position between the clamping sections when drawn together.

One form which my invention may assume 25 is exemplified in the following description and illustrated in the accompanying drawings, in which—

Fig. 1 is a cross section of a column form showing clamps applied.

Fig. 2 is a perspective view of one pair of 30 the clamping arms.

Fig. 3 is a perspective view of one pair of the clamping arms showing a modification of the same.

Referring to the drawings in detail and particularly to Fig. 1, A indicates a concrete column which has been poured. The numerals 2, 3, 4, and 5 indicate the forms surrounding the same, and the numerals 6, 7, 8, and 40 9 the clamping arms by which the forms are secured. The arms 6 and 8 are identical in construction and so are the arms 7 and 9. The perspective view in Fig. 2 illustrates one form of each arm; that is, arms 6 and 9.

45 Arm 9 consists of two pieces of strap iron 10—10 of suitable length. These straps are interspaced by means of spacing blocks such as indicated at 11, and the upper strap 10 is secured to the lower strap at one end as indicated at 12.

The lower strap of the arm 6 is extended beyond the upper strap and is provided with a reduced bent portion 21 having a cam surface 22 inclined at approximately 45° to the longitudinal axis of the arm 6. The arms 7

and 9 are identical in construction and each comprises a single piece of strap iron 10^a having spaced apertures arranged along the length thereof. Secured to each strap 10^a, by means of rivets or the like, are a pair 60 of spaced triangular plates 13 and 14. Each plate is secured to the strap 10^a on opposite sides thereof. The spacing between the plates is equal to the thickness of the strap iron and one end of the arms 6 and 8 can 65 be placed between the triangular shaped plates in a manner to be hereinafter described. The outer ends of the plates are provided with a plurality of aligned slots, as indicated at 15, 16, 17, 18, and 19. These 70 slots are provided for the reception of a wedging member such as indicated at 20. Each bent portion 21, on the arms 6 and 8, presents a shoulder and an inner cam face 22 which will always assume a position at 75 right angles to the slots in the plates 13 and 14. The wedges 20, when inserted, bear against the ends of the slots and the cam face 22, and a pull is exerted upon the arms when they are applied to the concrete forms, 80 as shown in Figure 1, which will be more than sufficient to retain the concrete forms in place, both before and after pouring the concrete.

Form clamps of the character described 85 are in more or less common use. They all meet with one common objection; to wit, that of pulling the forms out of square when applied. The main feature of the present invention is to prevent this objectionable feature, and means are therefore provided 90 whereby a limited movement is maintained between the connected ends of the arms. The arms 6 and 8 consist of the double spaced pieces of strap iron. The single piece of strap iron 10^a forming an integral part of the arms 7 and 9, passes between the spaced straps 10 of the arms 6 and 8, and between the spaced blocks 11. The spacing blocks are spaced substantially crosswise of 95 the strap iron sections forming the arms 6 and 8, but they are disposed on a slight angle. Their ends terminate in flat faces or shoulders, as shown at 11^b and 11^c and these shoulders form abutting faces with which 100 the bars 7 and 9 contact when inserted. When contact is maintained between the faces 11^b and 11^c and the opposed edges of the bars 7 and 9, a right angular position is assumed between the arms 7 and 8, and 105 6 110

and 9, respectively. For this reason it is impossible to pull the forms out of square when the clamping arms are applied.

In actual operation when the concrete forms have been placed in position, it is only necessary to apply the clamping arms, as shown in Fig. 1, i. e., the perforated ends of the bars 7 and 9 are passed between the interspaced straps or bars 10 of the arms 6 and 8, as shown in Fig. 2, and they are moved longitudinally until the desired adjustment is obtained. They are then secured against further movement by insertion of a pin 30. The bent ends of the arms 6 and 8 which are indicated at 21 are then swung inwardly between the triangular plates and the wedges 20 are inserted and driven into place. The clamping arms will thus draw the forms tightly together and the possibility of pulling or drawing the forms out of square is obviated.

If it is desired to remove the arms after the concrete has been poured and set, it is only necessary to release the wedges 30 and 25 to swing the arms 6 and 8 outwardly in the direction of the arrows *a* so as to free the bent ends 21 with relation to the triangular plates. This outward movement is permitted due to the angular position of the spacing blocks 11. When the arms 6 and 8 have been swung outwardly, it is also possible to remove them with relation to the interspaced straps 10, by removing the pins 30 and then pulling the bars 6 and 8 out from 35 between the straps.

Concrete columns are usually more or less standardized in size but larger or smaller columns are, nevertheless, constructed. To take care of the increases or decreases in size it is necessary to provide these several perforations indicated at 11^a so that the arms 7 and 9 may be lengthened or shortened. The bars 6 and 8 may be placed between the outermost spacing blocks 11 as 45 shown in Fig. 2 or the bars may be inserted between the other spacing blocks, and when this is done it is obvious that bars 7 and 9 are proportionately shortened. To prevent loss of the pins 30, a pair of cotter pins 31 are employed. One of the cotter pins may be permanently secured while the other is removable to permit the pins 30 to be shifted from one perforation to another. It sometimes happens that a column is hexagonal in cross section. In that instance six arms 55 may be used and the angular position of the spacing blocks 11 may be altered. Such changes are obvious and illustration is thought to be unnecessary, the main feature of this invention being that of maintaining a predetermined position or spread between the arms when they are being pulled together so as not to distort the shape of the forms to be clamped between the same.

65 Figure 3 shows a slight modification of

the invention. In this case the arms 6 and 8 are provided in the form of a single bar of strap iron having perforations 40 therein. The arm 6 has a bent end 22. The other arm 9, consists of a pair of spaced straps 70 10, which are riveted together at one end.

The triangular plates 13 and 14 are secured to the spaced straps 10 at the point where they are secured together. In this modification the spacing members 11 have 75 been omitted and in their stead have been substituted a series of staggered perforations 40. The arm 6 is adapted to be received between the straps 10 and secured in place by bolts 43 and 44 on either side thereof. The perforations 40 are so arranged that when the bolts 43 and 44 are inserted in any two adjacent perforations, the arm 6, when brought to bear against these bolts on opposite sides thereof will be at a right angle to the arm 9. Thus the bolts permit the arms to swing outwardly away from each other but serve to limit the inward swinging movement.

Having thus described my invention, what 90 I claim and desire to secure by Letters Patent is—

1. In a clamp of the character described, a clamping section comprising a pair of arms adapted to be connected at one end, and means at the connected ends of the arms for maintaining the arms at right-angles to each other, said means permitting a free spreading movement of the arms at the connected point in the opposite direction. 100

2. In a clamp of the character described, a clamping section comprising a pair of arms adapted to be connected at one end, and means at the connected ends of the arms for maintaining the arms at right-angles to each other, said means permitting a free spreading movement of the arms at the connected point in the opposite direction, and means permitting longitudinal adjustment of the arms at the connected point. 110

3. A mould clamp having in combination a plurality of bars laid so as to present their edges to the mould and to completely surround the mould, said bars being arranged in pairs and the ends of each pair being laid 115 angularly across each other, means for connecting the opposite ends of each pair of bars, means for drawing all of the bars together to clamp the mould, and means for preventing crossed arms from assuming an 120 angle therebetween of less than 90° but permitting outward swinging of the arms.

4. In a clamp of the character described, a clamping section comprising a pair of arms, one arm consisting of a single bar 125 having a plurality of interspaced perforations formed in one end and the other arm consisting of a pair of superposed bars, interspaced spacing blocks secured between the superposed bars of the last named arm 130

and forming pockets in which the perforated single arm may be inserted, said spacing blocks being disposed on an angle crosswise of the bars to maintain a predetermined spread between the bars in one direction and to permit free spreading of the bars in the opposite direction, and a pin insertable in the perforated single bar to prevent longitudinal movement thereof in one direction 10 with relation to the double bar.

5. A mould clamp having in combination a plurality of bars laid so as to present their edges to the mould and to completely surround the mould, said bars being arranged

in pairs one end of each pair being laid angularly across the other, means preventing longitudinal movement of the bars at the crossing point, means connecting the opposite ends of each pair of bars, and a wedge 15 cooperating with said means to draw all the bars tightly together to clamp the mould, and means on each pair of bars for maintaining them at right-angles with relation to each other when drawn together, said means permitting spreading of the bars in the opposite 20 direction.

JAMES F. COSTELLO.
